UNITED STATES PATENT OFFICE

2,458,020

COMBINED COSMETIC HOLDER AND
MIRROR OR THE LIKE

Donald E. Olsen, Chicago, Ill.

Application December 29, 1945, Serial No. 638,217

1 Claim. (Cl. 132—79)

1

This invention relates to combined cosmetic and mirror holder or the like and more particularly for a cosmetic for human lips commonly known as lipstick.

Among other objects, the invention aims to provide a new and improved lipstick holder and mirror having provision for protecting the lipstick and mirror when not in use, while bringing both into position for ready use when desired.

A further object is the provision of a unique mirror retaining member which at the same time serves as an ejector button for the lipstick and which is adapted for a variety of ornamentation and configuration.

Other objects and advantages will be apparent from the following description, taken together with the accompanying drawings, of a combined lipstick and mirror holder illustrative of the invention, and in which drawings—

Figure 1 is a perspective view showing a preferred form of the invention in closed position;

Figure 2 is a separated perspective view of the holder base and cover in separated relation, the mirror being shown open;

Figure 3 is a longitudinal sectional view of the assembled device as seen in Figure 1;

Figure 4 is a cross-section taken on the line 4—4 of Figure 3; and

Figure 5 is a somewhat diagrammatic perspective view of one form of hinge spring arrangement employable with the invention.

Referring in detail to the illustrative construction shown in the drawings, the numeral 10 indicates a base for a lipstick support which also includes a lipstick barrel 11, the base and barrel being advantageously formed of lightweight sheet metal. In this instance, the base and barrel are of rectangular box-like formation. A longitudinal cut, providing a slot 12, is made in one face of the barrel opening into its distal end 13 and continuing for a short distance as at 14 up one side of the enlarged base end 22 and into the adjacent face of the latter, 19.

Within the hollow interior of the base and barrel is located a metal cup 15 providing a mount for the lipstick itself 16, which latter may be of the usual material appropriate for application to a woman's lips, and which, since it is not the essential part of the present invention, need not be further described, it being sufficient to state here that the lipstick 16 is readily purchasable and may either originally or as a refill be associated with the device of the present invention by inserting the lipstick into the barrel 11 with one end of the lipstick, that is, its inner

2

end, inserted into the cup or socket-like mount 15 by a snug force fit.

The cup 15 has a slide member in the form of a lug 17, which extends outwardly through the slot 12—14 and sufficiently outwardly of the slot 12 so that when the cup is retracted, as shown in Figure 3, the button 18 on the lug 17 just overlies the base wall 19, in accordance with the present invention which will now be more particularly pointed out.

The companion part of the part just described comprises a box-like cover or container 20, having continuous rectangular walls upon five of its sides and having an open end 21 at its sixth side, which is one of its smaller ends and by which it is adapted to telescope over the barrel 11, thereby receiving the barrel within its hollow interior with the end 21 of the container 20 abutting the wall 22 of the base 10, at which time the lug 17 is retracted into the slot part 14. The part 20 may be also of light sheet metal.

Upon one of its walls, and in accordance with the present invention, upon its wall 23, which overlies the slot 12, the container 20 has hinged thereto as at 24, along one of its longitudinal edges an auxiliary cover plate 25 made up of an outer wall 26 and an inner frame 27 for a mirror or reflector member 28. In this instance, the mirror 28 is of the usual silvered glass construction and is insertable into the frame 27 through an open end 29 thereof, by means of which the mirror can be removed when desired for cleaning or replacement and returned to position or a new one inserted as desired.

35 When the mirror is closed, that is, when the plate 25 is swung to position abutting andlapping the container inner wall 23, the mirror is held in this position by the button 18 on the lug 17 which when the barrel and container are reciprocally telescoped, overlies closely the outer wall 26 of the mirror frame as well as the wall 19 of the base. In closed position removal of the mirror is desirably prevented, as clearly seen by the drawings.

45 As indicated in Figure 5, the hinge 24 is desirably a spring hinge, and, as here shown, may comprise a strip 30 of spring metal, such as brass, having one end anchored as by soldering it within a hinge sleeve 31 integral with the container wall 23. After being twisted in the direction of the arrow 32, the spring strip is anchored as by soldering or welding within a hinge sleeve 33 which is integral with the mirror frame 27. The spring strip may pass freely through intermediate intercalated hinge sleeves 34 and 35

which are integral with the container and 36 and 37 which are integral with the mirror frame.

Thus, when the base 10 and barrel 11 are withdrawn from the container 20, the spring 30 which has a torsional force tending to unwind it in the direction opposite to the arrow 32, opens the mirror into position convenient for the user holding say the container 20 in one hand and the base 10 in the other hand. The lipstick 16 may then be quickly and readily applied to the lips, which may be viewed in the mirror 28 while this is being done.

It will be understood that the lipstick as it is used up may have its distal end brought outwardly of the barrel end 13 sufficiently to permit application of the lipstick to the lips by sliding it by means of the slide member 18. When, however, the lipstick has been used and it is desired to reassemble the device into position as in Figure 1, the slide 18 may be manually retracted into the slot part 14, or, if not so manually retracted, it will be automatically retracted by the container 20 as the latter is telescoped over the barrel 11. While this is being done, the mirror plate 25 may be held closed until it is engaged under the button 18, whereupon, it is held in closed position until the lipstick is again withdrawn therefrom, at which time the mirror again springs automatically into open position for use.

So constructed and arranged the device is highly compact and the lipstick and mirror are protected so as to be safely dropped into a woman's pocket, hand-bag or cosmetic case without danger of becoming accidentally opened and permitting the lipstick to smear other contents thereof.

By making the spring hinge 24 with a relatively strong spring effect, as by the construction here shown, the force of the spring operating through the mirror plate 25 and the button 18 retains the container in position under the button 18 so as to guard against accidental exposure of the lipstick. At the same time, by making the lug 17 to slide not too freely in the slot 12-14, both the button and container are retained in position closely adjacent the base 10 until it is desired to manipulate the device into open position as already explained.

The metal surfaces of the parts referred to lend themselves to attractive ornamentation or to manufacture in the precious metals, such as, gold, silver or platinum. The button 18 may be attractively overlayed with an ornamental stone or

jewel-like member 38, for example, which might also in more expensive adaptations of the invention be a jewel such as a sapphire or the like. For less expensive embodiments of the invention, the surfaces of the metal parts might be baked enamel and the form of the parts might be varied from the rectangular outline here illustrated, as desired.

The foregoing suggested and such other changes as will be apparent to workers in the art may be made as fall within the scope of the appended claim without departing from the invention.

The invention having been described, what is here claimed is:

A combined lip-stick holder and mirror comprising a casing-like support, a slidable mount for a lip-stick in said support, an elongated container receiving telescopically the support and mount, a mirror frame hinged along one edge of said container for carrying a mirror on the inner face of said frame, said hinge including intercalated aligned hinge sleeves extending along one of the longer adjacent longitudinal edges of each of said mirror frame and container and including a relatively strong spring urging the mirror frame to open position, said spring comprising a torsion strip extending the greater part of the length of said longitudinal edge, and a button on said mount projecting outwardly thereof and adapted to overlie the mirror frame to retain it in closed position against the action of the torsion strip spring when the support and mount are telescoped into the container, said spring exerting a frictional force on the button tending to prevent separation of the support and container, and whereby the spring passes through intermediate ones of said hinge sleeves and is concealed thereby.
